(57) **CLAIM**

The ornamental design for a three in one paint roller with flexible handle, as shown and described.

DESCRIPTION

FIG. 1 is a front view (back view is mirror image thereof) of a three in one paint roller with flexible handle showing my new design;

FIG. 2 is a left side view thereof;

FIG. 3 is a right side view thereof;

FIG. 4 is a top view thereof;

FIG. 5 is another right side view in a condition of use on uneven surface; and,

FIG. 6 is a perspective view of a three in one paint roller with flexible handle in a condition of use on a flat surface.
